JAMES HOYT BROWN, OF DENVER, COLORADO.

NUT-LOCK.

1,194,944.

Specification of Letters Patent. Patented Aug. 15, 1916.

Application filed December 31, 1915. Serial No. 69,576.

To all whom it may concern:

Be it known that I, JAMES HOYT BROWN, a citizen of the United States, and residing at Denver, in the county of Denver and 5 State of Colorado, have invented certain new and useful Improvements in Nut-Locks, of which the following is a specification.

This invention relates to nut locks.

The object of the invention is to devise a 10 construction of nut lock which is efficient and positive in action, simple in form, inexpensive to make, easy to apply, capable of being packed in small bulk, light in weight, removable when desired without injury to a 15 thread, and which in addition to its function as a nut lock possesses a further function as a substitute and threadless nut.

With the foregoing and other objects in view which will appear as the description 20 proceeds the invention resides in the features of construction and in the combination and arrangement of parts hereinafter described and claimed, it being understood that changes in the features, combination 25 and arrangement can be made within the scope and as indicated by the variation in the phraseology, of the different claims, without departing from the spirit of the invention.

30 In the accompanying drawing forming part of the specification: Figure 1 is a side elevation, partly in section, of a bolt, a nut, and my improved device as it appears before it is screwed entirely home; Fig. 2 is a 35 view similar to Fig. 1 with the improved device screwed home; Fig. 3 is a plan view of the construction shown in Figs. 1 and 2; Fig. 4 is a perspective view of the improved device; Fig. 5 is a view similar to Fig. 1, 40 showing a modification; Fig. 6 is a plan view of the modification shown in Fig. 5; Fig. 7 is a perspective view of the modification shown in Fig. 5; Fig. 8 is a view similar to Fig. 1 of a second modification; Fig. 9 is a side elevation, partly in section, 45 of the second modification; Fig. 10 is a perspective view of the second modification; and Fig. 11 is a plan view of a third modification.

50 Like reference numerals indicate corresponding parts in the different figures of the drawing.

Referring to Figs. 1, 2 and 3, the reference numeral 1 indicates a bolt, 2 a nut and 55 A the improved locking device. The locking device A comprises a body portion 3

having therein an approximately circular opening 4. As indicated by the dotted lines in Fig. 3, the diameter of the opening 4 is less than the diameter of the circle 5, which 60 is defined by the outside circumference of the threaded portion of the bolt and is greater in diameter than the diameter of the circle 6 defined by the inside circumference of the threaded portion of the bolt. In 65 other words, in Fig. 3, the numeral 5 indicates the circle formed by the outer edge of the thread of the bolt. The dotted circle 6 indicates the innermost portion or root of the thread, and the circle 4 indicates the 70 opening in the body 3 of the nut lock. By proportioning the opening in the nut lock so that it is larger than the root of the 75 thread and smaller than the circle formed by the periphery of the thread, it is found 80 in practice that the body portion 3 can be applied to the thread of the bolt and screwed down thereon. This action is due to the fact that the proportioning of the opening in the body portion 4 to the inner and outer 85 diameters of the thread of the bolt causes approximately three-quarters of the edge of the opening 4 to be held in the threaded grooves of the bolt and the remaining fourth of the opening 4 being located outside of 90 the periphery of the thread of the bolt and crossing one of the threads in a diagonal direction.

By examining the three circles shown in Fig. 3, it will be observed that at the left 90 hand side of said figure the edge of the opening 4 in the nut lock is disposed in the root of the thread; the portions of the opening 4 which are shown respectively at the top and bottom of Fig. 3 are still locked in the 95 space between two threads, but are slightly spaced away from the root thereof; and the portion of the opening in the body portion 3 which is located at the right hand side of Fig. 3, is outside of the circle 5 and it is 100 this portion which passes diagonally around the outside of the thread. When the device is applied to the threads of the bolt, as shown in Fig. 1, by fitting the opening 4 over the bolt and turning the device down 105 as though it were a nut, the device assumes an inclined position with regard to the bolt, the body portion 3 being substantially parallel with the pitch or inclination of the threads of the bolt. After the nut lock is 110 screwed down sufficiently far to permit its lowest point to engage the nut which is to

be locked, a continued turning movement on the nut lock causes it to become positively locked on the bolt. This is due to the fact that when the device is screwed home the 5 tendency of that portion of the opening 4 in the body portion 3 which is nearest the nut 2 is to ride out on the inclined face 10 of the thread as shown in Fig. 1. As soon as one side of the body portion 4 tries to ride 10 out of the root of the thread the opposite portion of said plate 3 is drawn in tightly against the thread of the bolt at that portion of the thread which is crossed diagonally by the body portion 3. It is possible to 15 screw the nut lock down flat or substantially flat against the nut, as shown in Fig. 2, and in this position the device and the nut are firmly locked together.

In addition to the locking action which I 20 secure by making the opening 4 in the body portion 3 slightly larger in diameter than the circle formed by the root of the thread and slightly smaller in diameter than the circle formed by the outer periphery of the 25 thread, I secure a further locking action, in the modification shown in Figs. 1 to 4 by turning up two arms 11 and 12 on the body portion 3, the upper ends of which arms engage on the threads of the bolt. These arms 30 have sufficient resiliency to accommodate the bolt. The outer portions of the arms 11 and 12 serve to be engaged by a wrench in applying the device and for this same purpose the remaining two edges of the 35 substantially rectangular body portion 3' are turned up as indicated at 13 and 14.

The second modification shown in Figs. 5, 6 and 7 is the same as the first form of the invention, except that the arm 11 is 40 omitted and a straight side 15 is employed to receive a wrench, making three straight sides and one spring side as shown clearly in Fig. 7.

The third modification shown in Figs. 8, 9 45 and 10 is the same as the first form of the invention, except that both of the inturned arms 11 and 12 are omitted, and in their places are used the straight sides 16, thus producing a body portion having four up- 50 standing sides to receive the wrench and depending for its locking action on the opening in the body portion 3'. The inner edge of the opening 4' in this modification is sharpened or brought down to a knife edge 55 corresponding to the wedge shape in the groove of the bolt. When the device is screwed home against the nut, the sharpened edge of the opening 4' serves slightly to cut into the thread of the bolt at that 60 portion which is crossed diagonally by the body portion 1, thus positively locking the device in position. In practical use it is found that this engagement between one portion of the edge of the opening 4' and 65 one portion of the thread of the nut holds

the device positively in position and yet does not mar or ruin the thread of the bolt and does not prevent the nut lock from being readily removable whenever desired.

The construction shown in Fig. 11 is the 70 same as that shown in Fig. 9, except that the opening 4' in the body portion 3' is slightly oval. In this form a line taken across the narrowest portion of the oval is slightly longer than the diameter of the 75 root of the thread and slightly shorter than the diameter of the outer periphery of the thread, with the result that the device can be fitted over the bolt and screwed down against a nut when it reacts from the inclined position into a position parallel with the upper face of the nut, in which position it is tightly in engagement with the threads of the bolt and serves as an efficient nut lock. 80

The device of this invention is strong, simple and inexpensive in construction as well as thoroughly efficient and practical in operation. It can be used not only to lock a nut, but it is also capable of use as a substitute nut where light work only is required. 90

What is claimed as new is:

1. The combination with a threaded bolt and a nut or other body mounted thereon 95 and having a flat upper face extending at right angles to the bolt, of a nut lock comprising a body portion having a continuous flat surface to be turned against the flat surface of the nut or the like, thus tending to move the flat surfaces into approximate parallelism with each other when the device is turned home, said nut lock body having a substantially circular non-threaded opening therein with a continuous unbroken edge located normally in a plane parallel with the flat surface of the said body, said edge being narrow enough to fit into the groove of the bolt around substantially three-quarters of its circumference the remaining quarter of 100 said edge crossing one of the bolt threads in a diagonal direction sufficiently close to hold the other three-quarters of the edge in place within the thread groove. 105

2. The combination with a threaded bolt 110 and a nut or other body mounted thereon and having a flat upper face extending at right angles to the bolt, of a nut lock comprising a body portion having a continuous flat surface to be turned against the flat surface of the nut or the like, thus tending to move said flat surfaces into approximate parallelism with each other when the device is turned home, said nut lock body having a substantially circular non-threaded opening therein 115 with a continuous unbroken edge located normally in a plane parallel with the flat surface of said body, said edge being narrow enough to fit into the groove of the bolt around substantially three-quarters of its circumfer- 120

125

- ence, the remaining quarter of said edge crossing one of the bolt threads in a diagonal direction sufficiently close to hold the other three-quarters of the edge in place within 5 the thread groove, said nut lock body having a slightly resilient arm extending therefrom and engaging the bolt thread, the tension of said arm being altered when the angle of said body portion is changed by screwing it 10 home against the nut or other body.
3. The combination with a threaded bolt and a nut or other body mounted thereon and having a flat upper face extending at right angles to the bolt, of a nut lock comprising 15 a body portion having a continuous flat surface to be turned against the flat surface of the nut or the like, thus tending to move the flat surfaces into approximate parallelism with each other when the device is 20 turned home, said nut lock body having a substantially circular non-threaded opening
- therein with a continuous unbroken edge located normally in a plane parallel with the flat surface of said body, said edge being 25 narrow enough to fit into the groove of the bolt around substantially three-quarters of its circumference, the remaining quarter of said edge crossing one of the bolt threads in a diagonal direction sufficiently close to 30 hold the other three-quarters of the edge in place within the groove, said body having a plurality of slightly resilient arms extending therefrom and engaging the bolt thread, the tension of said arms being altered when the 35 angle of said body is changed by screwing it home, the continuous unbroken edge of said opening in the nut lock body being brought down substantially to a knife edge.

In testimony whereof, I, JAMES HOYT 40 BROWN, have signed my name to this specification this 30th day of December, 1915.

JAMES HOYT BROWN.
